PAUL N. VAN EPP, OF PORT CLINTON, OHIO, ASSIGNOR OF ONE-THIRD TO LAKE E. OWEN, OF SPRINGFIELD, MISSOURI

TROLLEY RETRIEVER

Application filed February 27, 1928. Serial No. 257,332.

My invention relates to trolley retrievers, and in general my object is to provide a durable self-acting device to retrieve or draw down a trolley following its accidental displacement from a trolley wire, and a further object is to provide simple means in such a retriever whereby replacement of the trolley to its original working position may be effected with ease and dispatch and the retriever reset for further retrieving operations.

In the accompanying drawings, Fig. 1 is a side elevation of the retriever, and Fig. 2 is a similar view of the retriever with portions of the casing in section to reveal interior parts in elevation. Fig. 3 is a vertical section of the retriever casing on line 3—3 of Fig. 2, the reel being omitted and the control plate being broken away in part to show the retriever spring and pawl. Fig. 4 is a vertical section of the casing on line 4—4 of Fig. 2. Fig. 5 is a front view of the locking pawl, and Fig. 6 is a rear view of the same pawl. Fig. 7 is a vertical section of the retriever on line 7—7 of Fig. 2. Fig. 8 is a sectional view of the retriever corresponding in part to Fig. 7, one half of the reel being broken away and a portion of the control also broken away to reveal the working parts. Fig. 9 is a sectional view, corresponding in part to Fig. 2, showing the flange portion of the reel in section. Fig. 10 is a sectional view of the casing, reel and control plate, the main spring and the locking pawl being shown in elevation. Fig. 11 is a sectional view corresponding to Fig. 8, showing the working parts locked together as they appear after the retriever spring has been rewound but before the locking pawl has been arrested. Fig. 12 is a horizontal section and plan view of the retriever on line 12—12 of Fig. 11. Fig. 13 is a diagrammatic view showing the retriever spring wound and contracted with the locking pawl in stop engagement with the flange or rib 48 and in the position which it assumes before its orbital travel is reversed to engage locking shoulder 36.

The invention comprises a casing 2 in the form of a hollow cast metal body of circular form having a recessed base or rear portion 4

of reduced diameter which is provided with lugs 5 to permit the retriever body to be detachably connected to a suitable bracket of the type and kind customarily used upon an electrically driven vehicle having a trolley pole held in running engagement with a trolley wire by a powerful spring or set of springs mounted upon a swiveling base. A cover plate 3 having integral arms 6 of angular shape is secured by bolts 7 to a pair of ears 8 at the front edge of casing or body 2, and an additional connection is provided by a screw-threaded shaft or bolt 9 which extends axially through cover 3 and the body. Shaft 9 also serves to support several rotatable parts internally of the casing, including a rope winding reel R. Thus shaft 9 is screw-connected to a central hub 10 within the recessed base 4, and a nut 11 is used to lock the bolt against rotation. The front end of the shaft 70 passes through a hollow hub 12 which extends inwardly toward the casing, the outside of the hub being of eccentric form to provide a connecting shoulder 14 for the hook end 15 of a coiled spring 16 which is confined 75 within a circular chamber 17 in reel R. The rope 19 passes from the reel through an open space 20 which separates the front plate from the casing body, one end being detachably connected to a wire loop 21 pivotally secured 80 to the reel. The outer coil of spring 16 is provided with a supplementary extension or strip 22 of heavier spring material having slip locking connection with a series of beveled projections or teeth 18 extending inwardly from the circular wall of the reel. Spring 16 is a free flexing spring which functions to take up the slack in the trolley rope during the normal play of the trolley in its travel over a trolley wire suspended at varying 90 heights above the car track at different places along the line. A series of radial ribs 25 extend into chamber 17 from the flat side wall 26 of the reel, and spring 16 bears at its edges against said ribs.

Two governor arms 28 are pivotally mounted outside upon wall 26 of reel R, and these arms are linked together for joint movement when centrifugally actuated, each arm having a spring 29 connected thereto to re-

verse its movement and to hold the longer end of one of the arms against a short post 30 when the reel is at rest or rotating slowly, see Fig. 8. When the reel is rapidly rotated, as occurs when the trolley jumps the trolley wire, the governor arms fly outwardly against stop lugs 32 on wall 26 of the reel, and the end of one governor arm strikes a lateral projection 32 on a control plate or flat 10 disk D which is rotatably mounted upon shaft 9 directly opposite wall 26. The shock or impact rotates said disk a short distance in a clockwise direction against the tension of a strong retriever spring S which is wound 15 up and held in that condition by a gravity locking pawl P which is pivotally connected to a lug 33 at one side of the disk. Locking is effected by a hook projection 43 at one end of pawl P, when said projection rests 20 within a notch 35 between two shoulders 36 and 37, respectively, of different height formed at the ends of two eccentrically curved rib portions integral with the inner wall of casing 2. Disk D is provided with a 25 toothed hub 38 over which a spring-winding arbor 39 is sleeved and with which it is detachably interlocked, and the retrieving spring S has its inner coil hooked to or detachably connected with a shoulder 40 on 30 said arbor 39, see Fig. 4. The outer coil of the retriever spring S is reenforced and made stiffer by a supplemental piece 41 of spring metal and the end thereof secured by a bolt 42 to the circular wall of base portion 4 of 35 the casing. Accordingly when the retriever spring is wound up its outer coil is curled apart from the encircling wall of the casing, which condition permits the gravity locking pawl P to swing inwardly at its locking end 43 toward the spring arbor when said end is 40 released from the undercut locking shoulder 36 on casing 2. Release is effected when disk D is rotated suddenly in a spring winding direction by the trolley when it jumps off 45 the trolley wire, the sudden rotation of the reel causing the locking extremity 43 of pawl P to strike the corner of shoulder 37 on stationary body 2 and to rebound and swing inwardly toward the spring arbor. However 50 the retriever spring S is more powerful than the springs which uphold the trolley, and therefore the trolley is drawn down or retrieved very promptly after the inward rebound of the locking pawl occurs. The retrieving or unwinding movement of the retriever spring S reverses the direction of 55 rotation of disk D and the pawl P on the disk moves in a counter-clock-wise direction while the locking end 43 of the pawl is in a retired 60 position or where it will not engage shoulder 36 during such reverse movement. In this unlocked position of the pawl a spring-pressed dog 44 carried by the pawl near its pivot projects outwardly through one of a 65 series of notches or openings 45 in the flanged

rim 46 of reel R, a positioning of parts which later permits rewinding and resetting operations. In that connection it should also be noted that locking pawl P is provided with a beveled lug or pad 47 at one side opposite the nose of the spring-pressed dog 44, and that this lug or pad projects toward and overlaps the last coil of the retriever spring S which is of sufficient width to protrude a short distance into the chamber wherein disk D and pawl P rotate. A narrow flange 48 is cast on body 2 as a continuation of the last coil of the retriever spring where reenforced and made stiffer by piece 41, and this flange 48 extends part way around the circular border edge of the base recess containing spring S. Accordingly when the retriever spring is unwound as occurs after the retrieving operation the last coil of the spring and flange 48 provide a circular track around which the pad 47 on pawl P must ride for an interval during the rewinding of the retriever spring. In that interval pawl P is prevented from swinging on its pivot thereby holding its locking end 43 in a retired or unlocked position and the dog 44 in pressing engagement with the notched rim 46 of the rope winding reel R. Thus assuming that retrieving of the trolley has been automatically accomplished reel R is locked by the governor arms 28 to the revoluble disk D which is connected by arbor 39 to the retriever spring S and therefore still under tension although the spring is now unwound in greater or lesser degree dependent upon the counter pull of the trolley springs. To restore the trolley to the trolley wire and to reset the working parts for retrieving operations again the retriever spring S must be rewound. The present device has been designed to simplify that operation, so that the operator is only required to pull upwardly on the trolley rope and rotate reel R until the retriever spring is completely wound up whereupon certain actions occur automatically to reset the working parts in their original retrieving relations. To begin with, winding of the retriever spring by manual pull on the rope and rotation of the reel requires a locking connection between the reel and disk D which locking connection is provided by the governor arms 28 which remain interlocked with an integral projection 32 on disk D after retrieving, inasmuch as unlocking thereof has been prevented by the pivoted dog 44 on the pivoted pawl P while spring S is in a run down condition, and during such time as pawl P is disconnected from body 2. Thus by rotating the reel in a clockwise direction the retriever spring S will be wound up and contracted, and at the finish of this winding movement of the spring the outer coil of the spring is drawn toward the axis of the spring in sufficient degree to permit the pad 47 on pawl P to also move 110 115 120 125 130

toward the same axis, the pawl dropping by gravity and turning on its own pivot pin 33 until the locking end 43 of the pawl engages the inclined surface leading to the notch 35. 5 As the locking end of the pawl drops the pad 47 on the other side of the pivot of the pawl moves into a position where it will strike the end edge 49 of flange 48 on body 2 during the orbital travel of pawl P around the spring, thereby arresting all further 10 spring winding movements. The operator then relieves the pull on the trolley rope which permits the wound retriever spring to reverse the movement of reel R and disk D, 15 thereby carrying the locking end 43 of the pawl backward, into engagement with the undercut shoulder 36 on body 2 with locking effect as at the beginning. As the locking pawl P falls by gravity into its place in notch 20 35 the spring-pressed dog 44 is withdrawn from the border slot or opening 45 in the rim or flange 46 of reel R, thus permitting the reel to turn in a rope unwinding direction under the control of the weaker spring 16 and the 25 trolley springs. Release of dog 44 also causes the governor arms 28 to be disengaged from the projection 32 on disk D and to resume a normal inactive position as at the beginning. Thus, it will be seen that the resetting of the 30 retrieving parts is simplified to such an extent that the operator need only pull upwardly on the trolley rope after a retrieving operation until the retriever spring is wound up and the locking pawl is locked automatically. 35 and the reel itself is unlocked to take up the slack in the trolley rope automatically. Another important advantage is that the trolley, after being retrieved and drawn down, can not be restored to the trolley wire 40 without winding the main retriever spring to its maximum tension. The operator must pull the trolley rope upwardly and rewind it from the reel until the main spring is fully wound up and completely contracted, otherwise 45 the locking dog 44 on pawl P maintains the locking connection between the reel and the main spring. Thus release is not effected until the outer reenforced coil of the main spring is contracted and drawn away from 50 pawl P with a corresponding following movement of the pad 47 on the pawl which will bring the pad into stop relation with the end edge 49 of flange 48 on body 2. Until that stage in winding operations of the main 55 spring is reached the beveled end of pad 47 rides over the beveled end edge 49 and around flange 48. When the spring is completely contracted the pad functions as a positive stop to prevent further unwinding of the 60 rope from the reel, and then a slight reverse movement will permit the pawl to gravitate into locking position with shoulder 36 on body 2 as at the beginning.

What I claim is:

65 1. In a trolley retriever, a rope winding

reel, separate coiled springs, of different power for controlling the rotatable movements of said reel, automatic means for connecting the more powerful spring with said reel to effect retrieving when said reel is rapidly revolved, locking means for said automatic means to hold said powerful spring in connection with said reel and means for automatically disconnecting said powerful spring from said reel when said reel is rotated in a rope unwinding direction to wind up said spring subsequent to a retrieving operation. 70

2. In a trolley retriever, a rope winding reel, a coiled take-up spring for rotating said reel idly under normal operating conditions, a coiled retriever spring for rotating said reel in a rope-winding direction to retrieve a displaced trolley, and means for effecting a working connection between said retriever spring and reel when the trolley 80 is displaced, including a locking device engageable with said rope winding reel and said retriever spring and controlled by the expansion and contraction of the coils of said retriever spring. 85

3. A trolley retriever, including a rope-winding reel, two coiled springs for rotating said reel including a retriever spring, means for connecting one of said spring automatically to said reel to retrieve the trolley, 90 and locking means for said retriever spring controlled by the contracting movements of one of said springs, said locking means including means to maintain said connection until the retriever spring is completely rewound and locked. 95

4. In a trolley retriever, a casing, a rope-winding reel, a coiled retriever spring for said reel, a control plate connected with said spring, centrifugal locking devices for said plate carried by said reel, and a locking pawl for said control plate engageable with said casing, and said retriever spring when unwound and expanded operating to hold said locking pawl inactive until the retriever spring is completely wound and contracted. 105

5. In a trolley retriever, a casing, a rope-winding reel mounted upon said casing, a coiled spring to rotate said reel for taking up the slack in the trolley rope, a convolute spring to rotate said reel for retrieving the trolley, a control plate connected to said retriever spring, centrifugal locking devices on said reel for said plate, a locking pawl on said plate engageable with said casing, a locking projection on said pawl engageable with said plate, and means on said pawl engageable with the outer convolution of the retriever spring to prevent said pawl from locking to said casing until said spring is fully wound and contracted in resetting the parts for retrieving operations. 115

6. A trolley retriever, including a casing having a locking shoulder internally, a control plate carrying a gravity pawl having a 120

projection adapted to interlock with said shoulder; and a retriever spring coiled within said casing and engageable with said pawl and operating when unwound to withhold said projection apart from said locking shoulder.

7. A trolley retriever, including a casing, a retriever spring confined within said casing; a rotatable plate connected to said spring, a gravity pawl secured to said plate having a hook projection, spaced shoulders within said casing adapted to be engaged by said projection upon rotatable movements of said plate, and means adapted to prevent said pawl from dropping by gravity into locking position opposite said shoulders until the retriever spring is completely wound and contracted.

8. A trolley retriever, including a casing, a convolute retriever spring coiled within said casing, said casing having a projection bordering the outer convolution of said spring, and a rotatable control plate connected to said spring having a gravity pawl adapted to interlock with said casing when said spring is wound, said pawl when disengaged from the casing being arranged to travel in an orbit around said spring and to be brought into stop contact with said projection upon winding the spring and contracting its outer convolution.

9. In a trolley retriever, a casing having a base recess, a convolute retriever spring confined within said recess and projecting partly therefrom, a rope-winding reel, rotatable controlling devices for said reel connected to said spring, including a locking pawl arranged to travel in contact with the outer convolution of said spring when rewinding said spring after retrieving operations, and a stop element on said casing in the path of a protruding portion of said pawl.

10. A trolley retriever, comprising a casing having spaced shoulders internally thereof, a convolute spring confined within said casing, a stop element adjacent said spring, a rope-winding reel, a rotatable control plate, centrifugal locking devices for said reel and plate, a gravity pawl mounted upon said plate adapted to engage said spaced shoulders in reverse rotatable movements of said plate, and a projection on said pawl adapted to ride upon said convolute spring and to engage said stop element when the spring is rewound after retrieving operation.

11. A trolley retriever, comprising a casing, a retriever spring connected to said casing, a rope-winding reel, a coiled spring connected to said reel, a rotatable control plate having lugs, centrifugal locking members on said reel adapted to engage said lugs when the reel is suddenly rotated, a gravity locking pawl mounted upon said plate, a locking portion and an impact portion upon said casing engageable by said pawl, a dog on said pawl

to interlock with said reel, a projecting pad on said pawl engageable with the outer convolutions of the retriever spring, and a stop on said casing engageable by said pad when the retriever spring is rewound.

12. A trolley retriever, comprising a casing having a base recess, a convolute retriever spring having its outer convolution attached to said casing and projecting beyond said recess, a projection at the border of said recess, a rotatable control plate having an arbor connected with the inner convolution of said spring, a gravity pawl pivoted to said control plate having a pad at one end adapted to ride upon the outer convolution of said spring and to engage said border projection, a locking shoulder on said casing for said pawl, means adapted to swing said pawl inward toward said spring during orbital travel of said pawl, a rope-winding reel having a notched flange, centrifugal locking members on said reel and striking lugs therefor on said control plate, a spring-pressed dog on said pawl adapted to interlock with the notched flange of said reel, and a second convolute spring connected with said reel and a part of said casing.

13. A trolley retriever, including a casing, a rope-winding reel, a main spring connected to said casing, a secondary spring having slip connection with said reel, a rotatable plate carrying a locking pawl for said main spring and plate, means for unlocking said pawl automatically upon rapid rotation of the reel, means for holding said locking pawl unlocked until the main spring is rewound, and means for locking said reel and plate together when the pawl is unlocked.

14. A trolley retriever, comprising a casing having a base recess, a main spring coiled within said recess having its outer coil secured to the casing, a control plate having an arbor connected to the inner coil of said spring, a gravity pawl pivoted upon said plate and releasably to said casing, a pad on said pawl engageable with the outer convolution of said main spring, a stop for the pad on the casing, a rope-winding reel having a notched flange, a dog on said pawl engageable with said notched flange, lugs on said control plate and centrifugal locking members on said reel adapted to interlock with said lugs when the reel is rapidly rotated, a coiled secondary spring having its outer coil in frictional slip engagement with said reel, and a cover plate for said casing having a hub connected to the inner coil of said secondary spring.

In testimony whereof I affix my signature.

PAUL N. VAN EPP.
